CHARLES LE G. FORTESCUE, OF PITTSBURGH, PENNSYLVANIA, ASSIGNOR TO WESTINGHOUSE ELECTRIC AND MANUFACTURING COMPANY, A CORPORATION OF PENNSYLVANIA.

MULTIPHASE RECTIFYING SYSTEM.

1,241,505.

Specification of Letters Patent.

Patented Oct. 2, 1917.

Application filed March 30, 1914. Serial No. 828,210.

To all whom it may concern:

Be it known that I, CHARLES LE G. FORTESCUE, subject of the King of Great Britain, and a resident of Pittsburgh, in the 5 county of Allegheny and State of Pennsylvania, have invented a new and useful Improvement in Multiphase Rectifying Systems, of which the following is a specification.

10 My invention relates to systems for the rectification of alternating currents.

The object of my invention is the connection of rectifying units in such a manner that they may be used at their highest efficiency to insure a high power factor in the 15 system and a resultant direct current of nearly uniform value.

By the use of my invention I am enabled under certain conditions, to place a portion 20 of my asymmetric conductors in each of several containers without the necessity of providing separate maintenance for each of said containers.

Referring to the accompanying drawing, 25 Figure 1 is a diagrammatic view of my system as applied to a six-phase star interconnected source of alternating currents which are rectified by means of two three-phase mercury arc rectifiers; Fig. 2 is a wave diagram of the potentials in Fig. 1; Fig. 3 is a diagrammatic view of my system as applied to an interconnected quarter-phase source of alternating currents, the rectification being by asymmetric conductors of the electro- 30 lytic type; Fig. 4 is a wave diagram of the potentials in the circuit of Fig. 3; and Fig. 35 5 is a diagrammatic view of a modification of the system shown in Fig. 1.

In the rectification of alternating currents, 40 it is frequently desirable to connect the secondaries of a pair of three-phase transformers as shown at 1, 2, 3 and 1^a, 2^a and 3^a in Fig. 1. This forms a source of six-phase alternating currents which, when rectified, 45 make up a practically uniform direct current. For mechanical reasons, it is extremely difficult to place more than three anodes of the heavy current type in a single mercury vapor arc rectifier. Accordingly, I 50 have provided two containers 4 and 5, preferably of metal, and have placed therein anodes 6, 7, 8 and 9, 10, 11 respectively. The method of connection which would be followed by one who had studied the prior art 55 would be to connect the two cathodes by a

bond, thus forming the electrical equivalent of a single container having six anodes. The direct current load 15 would be connected between this bond and the neutral point 16 of the transformer. The diagram 60 of Fig. 2 shows that, under these conditions, current will be flowing from each anode and obtained from each transformer winding for one-sixth of each cycle. Taking, for example, the wave 1^a which flows from anode 9, 65 current will not begin to flow until the potential of anode 9 is higher than that of anode 6 which is transmitting the wave from winding 1. Accordingly, anode 9 will not come into action until the point 17 (Fig. 2) 70 is reached and it will cease action at the point 18 when anode 7, connected with winding 2, exceeds it in potential. While this system of connections would operate to produce a direct current, represented by a 75 line 17, 1^a, 18, 2, 19, 2^a, 20, the system would be extremely inefficient in its use of the transformers, since each separate winding is in action for only one-sixth of the time, and it would also have an exceedingly poor 80 power factor. Furthermore, the rectifiers 4 and 5 would not be self-maintaining, as is the case with an ordinary three-phase rectifier, because of the fact that the ripple 17, 18, would flow in container 5, ripple 18, 19 85 in container 4, ripple 19, 20 in container 5, etc. Thus, in each container there is an arc during only every other sixth of a cycle, giving ample opportunity for the negative electrode reluctance to reestablish itself and 90 necessitating expensive and cumbersome maintaining devices.

I obviate all the above objectionable features of a direct bond between cathodes 12 and 14 by inserting in the connection between these electrodes an inductive winding 24 which may, for the purpose of this case, be considered as an auto-transformer. I connect a direct-current load between an intermediate point of this auto-transformer and the neutral point 16 of the alternating-current source. The point of connection to winding 24 is preferably the mid point thereof. The operation of the system is as follows: wave 1 will flow from anode 6 and will not be extinguished at point 17 by the rise of potential of anode 9 but will continue to flow until the point 21 is reached, when, because of the rising potential of anode 7 in the same container, the current 110

flow will be transferred thereto. This feature, that each anode carries current until another anode in the same container comes into action, causes each rectifier to be self-maintaining. The two ends of auto-transformer 24 will alternate in potential, and the mid point 25 will always assume an intermediate potential which may be plotted as an undulatory line 26, 17, 27, etc., having 5 a maximum potential point slightly less than the maximum potential of the supply. The back electromotive force of the load is shown by a line 28—29.

By the use of the auto-transforming device 24, each transformer winding and each anode is active for one third of each cycle rather than for a sixth thereof; a much better power factor for the system is secured; and the resultant direct-current wave 10 form is as good as, or better than, that derived from a direct bond between cathodes. The auto-transformer 24 may be made extremely compact, since it operates at six times the frequency of the source, and the 15 difference of potential across it is only about five per cent. of the voltage of the direct-current system.

Referring to Figs. 3 and 4; 30, 31, 32, 33 is a quarter-phase interconnected source of 20 alternating currents, having a neutral point 34. Connected to each winding is an asymmetric conductor of the electrolytic type, shown at 35, 36, 37 and 38. Each electrolytic device comprises an aluminum container which is the active electrode and to 25 which is attached the connection from the transformer; and a central electrode of some inactive material, such, for example, as iron or carbon. Asymmetric conductors 30 of this type are so common and well known in the art as to need no further detailed description. Electrolytic devices 35 and 36 have their inactive electrodes connected by a bond 39, and electrolytic devices 37 and 38 35 have their inactive electrodes connected by a bond 40. Connecting the bonds 39 and 40 is an inductive device 41 corresponding to the auto-transformer 24 in Fig. 1, the intermediate point 42 thereof being connected 40 through a load 66 with the neutral point 34 of the alternating-current source.

Referring to Fig. 4, the waves from windings 30 and 32 are represented as 30 and 32, respectively, and those from windings 31 45 and 33 as 31 and 33, respectively. The back electromotive force of the load is shown by a line 51—52. Without the device 41, wave 31 would cease to deliver current at the point 44, wave 32 at point 45, etc.; and the direct-current wave form would be shown by a line 31, 44, 32, 45, etc. With the device 41 50 in use, however, wave 31 will continue to deliver current to the point 49, wave 32 to the point 53, etc. On a pure resistance load, 55 wave 31 will continue to deliver current up

to point 57; wave 32 up to point 58, etc. Thus, it is seen that, without device 41, each transformer winding is in use but one-fourth of the time on any type of load; with the device in use and a load having a back electromotive force, each winding is in use between one-fourth and one-half the time; and with device 41 and a resistance load, each winding is in use for one-half the time. The resultant wave form on a load of back electromotive force 51—52 is shown by a line 43, 59, 44, 60, 45, etc., and on a pure resistance load by a line 43, 62, 44, 63, etc., having ripples of four times the frequency of the source.

The auto transformer may be placed between the load and the source, if desired, and similar results obtained. I have shown this modification of my invention in Fig. 5, wherein 59 and 60 are two sources of three-phase alternating currents, having a phase displacement of 60° . An auto transformer 61 is connected between the two neutral points and to its mid point is attached a wire 62 from a load 63. The cathodes of 65 two three-phase mercury arc rectifiers 64 and 65 are bonded by a wire 66, to which is attached the other terminal of the load 63. In operation, the two neutral points alternate in polarity to the same extent as do the 70 cathodes in the system of Fig. 1, with resultant variations in the potential difference impressed upon the rectifiers. In consequence, each alternating-current wave will flow for one third of a cycle as in the system of Fig. 1, rather than for one-sixth of a cycle.

What I claim is:

1. The combination with a source of multiphase alternating currents provided with a neutral point, of two groups of asymmetric conductors, a connection from each phase of the source to a terminal of one of said asymmetric conductors, all such terminals being of like polarity, successive phases being connected alternatively to asymmetric conductors of each group, and all the terminals of the other polarity in each of the groups of asymmetric conductors being in electrical connection with each other, a conductor containing an inductive winding connecting each of said groups of common terminals, and a circuit between an intermediate point of said inductive winding and the neutral point of the source of alternating currents.

2. The combination with a polyphase source of alternating currents provided with a neutral point and having an even number of phases, of two groups of asymmetric conductors, a connection from each of one half of said phases to a terminal of an asymmetric conductor of one of said groups, a connection from each of the remaining phases to a terminal of an asymmetric conductor of the other of said groups, said terminals all be-

ing of like polarity, and all the terminals of the other polarity in each group being in electrical connection, a connection including an impedance device between the common terminals, and a load circuit connecting an intermediate point of the impedance device and the neutral point of the source of alternating currents.

3. The combination with two polyphase sources of alternating currents having the same phase angle and differing from each other in phase by one-half the common phase angle, each of said sources being provided with a neutral point, of two groups of asymmetric conductors, there being as many asymmetric conductors in each group as there are phases in each source, a connection from each phase of one source to a terminal of an asymmetric conductor in one group, a connection from each phase of the other source to a terminal of an asymmetric conductor of the other group, all of said terminals being of the same polarity, all of the terminals of the other polarity in each group being in electrical connection, a connection including an impedance device between said common terminals, and a direct-current load circuit between an intermediate point of the impedance and the neutral points of the two sources.

4. The combination with two sources of three-phase alternating currents having a common neutral point and differing from each other by a phase angle of substantially 60°, of two three-phase rectifying devices, a connection between each phase of one source and a terminal of one of the rectifying devices, a connection between each phase of the other source and a terminal of the other rectifying device, all of said terminals being of the same polarity, all the terminals of the opposite polarity in each rectifying device being in electrical connection, a con-

nnection between said common terminals including an auto-transformer, and a direct current load circuit between an intermediate point in said auto-transformer and the common neutral point of the two sources.

5. The combination with two sources of three-phase alternating currents having a common neutral point and differing from each other by a phase angle of 60°; of two three-phase mercury arc rectifiers, a connection between each phase of one source and an anode of one rectifier, a connection between each phase of the other source and an anode of the other rectifier, a connection between the cathodes of the rectifiers including an auto-transformer, and a direct-current load circuit between the mid point of said auto-transformer and the common neutral point of the two sources of alternating currents.

6. The combination with two sources of alternating currents having the same phase angle and differing from each other in phase by one-half the common phase angle, of two groups of asymmetric conductors, there being as many asymmetric conductors in each group as there are phases in each source, a connection from each phase of one source to a terminal of an asymmetric conductor of one group, a connection from each phase of the other source to a terminal of an asymmetric conductor of the other group, all of said terminals being of the same polarity, and means whereby there will be working current flowing in each group of asymmetric conductors at all times.

In testimony whereof, I have hereunto subscribed my name this 23rd day of March, 1914.

CHARLES LE G. FORTESCUE.
